United States Patent [19]

Chang et al.

US00D358935S

[11] Patent Number: Des. 358,935

[45] Date of Patent: ** Jun. 6, 1995

[54] COMPUTER CASE

- [76] Inventors: **S. J. Chang**, 13-3 Sanjung Dong
Joon-Ku, Burchum City,
Kyunggi-Do, Rep. of Korea; **Joseph J. Berman**, 55 Mountain View Ter.,
Hillsdale, N.J. 07642
- [**] Term: **14 Years**
- [21] Appl. No.: **14,581**
- [22] Filed: **Oct. 22, 1993**
- [52] U.S. Cl. **D3/289; D3/276;**
D3/900
- [58] Field of Search **D3/273, 276, 285, 288,**
D3/289, 301, 303, 900; 190/100, 110, 111, 115,
900, 901, 903
